DRILLING APPARATUS

Win W. Paget, Michigan City, Ind., assignor to
Sullivan Machinery Company, a corporation of
Massachusetts

Application March 5, 1940, Serial No. 322,267

27 Claims. (Cl. 255—47)

This invention relates to drilling apparatus, and more particularly to improvements in rotary drilling apparatus of the high speed type especially designed for use in boring holes in relatively hard material such as hard rock or the like.

An object of this invention is to provide an improved drilling apparatus. Another object is to provide an improved drilling apparatus having improved feeding means and improved means for controlling the feeding means. A further object is to provide an improved fluid actuated feeding means for a rotary drilling apparatus, and means responsive to the resistance to drill bit rotation for automatically controlling the feeding pressure. Yet another object is to provide an improved fluid actuated feeding means having an improved means for controlling the flow of actuating fluid to and the venting of fluid from said feeding means. Another object is to provide an improved rotary drilling apparatus of the high speed type having improved means for automatically controlling the feeding pressure on the drill bit so as to maintain an automatically controlled and limited feeding pressure during the drilling operation. A further object is to provide an improved feed controlling means which has different degrees of responsiveness to different degrees of resistance to drill bit rotation whereby different feed controlling functions may be effected. Still another object is to provide an improved feed controlling means responsive to the resistance to drill bit rotation for regulating the flow of actuating pressure to the feeding means within predetermined degrees of resistance to drill bit rotation and for interrupting such flow when the resistance to drill bit rotation reaches a predetermined point, and embodying means for automatically venting the feeding pressure when such point is exceeded. A still further object is to provide an improved feed controlling means for automatically interrupting the forward feed when the torque on the drill bit rotating motor reaches a predetermined point, and embodying means for venting the forward feeding pressure when such torque becomes excessive. A still further object is to provide an improved torque-controlled valve means responsive to torque variations resulting from changes in load on the drill bit rotating motor for automatically controlling the feeding means. Another object is to provide an improved automatic feed controlling means whereby manual feeding of the drill may be at any time during the drilling operation, and without any manipulation of transfer mechanism, supersede the automatic feeding operation.

A still further object is to provide an improved manual drill feed operating means associated with the fluid actuated feeding means whereby manual feed of the drill bit may be instituted at any time, at will, during the drilling operation and automatically interrupt feed by the fluid actuated feeding means, and having improved control means whereby when an excessive load is applied to the bit rotating motor by the manual feeding means the fluid in the fluid actuated feeding means is automatically vented. Another object is to provide an improved automatic feed controlling means whereby manual control of the feed effecting elements may be initiated at any time during the operation of the automatic feeding devices simply by commencing to operate the manual feed effecting means, and whereby instantly upon the cessation of operation of the manual devices automatically controlled feed will be automatically resumed. A still further object is to provide an improved manual drill feed operating means associated with automatic fluid actuated feeding means whereby the drill bit may be manually fed at will during the drilling operation and the operation of the automatic fluid actuated feeding means be automatically resumed when manual feed is discontinued. A still further object is to provide in combination with fluid actuated feeding means having automatic control of the supply of fluid feeding medium, an improved manual feed operating means, and to provide in the control means devices whereby when an excessive load is applied to the drill bit rotating motor through the manual feeding means the fluid feeding medium may be automatically vented. Another object is to provide for a drilling motor improved selectively operable manual and automatic feeding systems each utilizing in a common chamber a body of fluid feeding medium for the transmission to the drilling motor of a feeding pressure, and providing means whereby during the operation of one of said feeding systems automatic control of fluid feeding medium supply is accomplished and during operation of the other automatic control of fluid feeding medium venting is accomplished. Still another object is to provide an improved drilling apparatus embodying mechanism utilizing a fluid medium for the transmission of feeding pressures to the drilling motor and including means for selectively effecting manual or automatic feed, and means responsive to the resistance to drill bit rotation under either condition for regulating the volume of the fluid feeding medium. These and other

objects and advantages of the invention will, however, hereinafter more fully appear.

In the accompanying drawings there is shown for purposes of illustration one form which the invention may assume in practice.

In these drawings—

The present invention is an improvement over that disclosed in my copending application Serial No. 268,792, filed April 19, 1939. In my earlier filed application I disclose mechanism including coacting cylinder and piston elements for effecting pressure fluid operated forward feed of a bit rotating motor under automatic torque control and for effecting pressure fluid operated retraction of the bit rotating motor, together with manual means for bodily advancing and retracting the bit rotating motor and its pressure fluid operated feeding means. With such a mechanism, when it is desired to utilize the manual feeding means to reposition the parts of the pressure fluid operated feeding devices to extend the feed effectible by the latter it is necessary to reverse the manual control valve whose position determines the direction of relative movement between the elements of the pressure fluid operated feeding mechanism. In the normal mode of operation of such a structure the fluid actuated feeding means is first operated until it completes its forward feeding stroke. The feed piston of the fluid actuated feeding means is then retracted, and thereafter the manual feeding means is operated to feed the feed cylinder and the feed piston, both, of the fluid actuated feeding means into a new feeding position, and finally the fluid actuated feeding

means is again operated to effect another forward feeding operation. With the mechanism illustrated in this present application, as will be duly pointed out, it is unnecessary to effect a retraction of the feed piston relative to the feed cylinder in order to provide for extension of the pressure fluid operated feeding of the bit rotating motor, and improved means is provided whereby, within the range permitted by the apparatus, the manual feeding means may be operated at any time at will while drilling is going on automatically to discontinue the normal pressure fluid operated feeding operation and to effect a readjustment of the parts of the feeding devices, while drilling continues, without any manipulation whatever of the main manual feed control valve.

In the illustrative embodiment of the invention herein disclosed there is shown a rotary drilling apparatus of the high speed type especially designed for use in drilling hard rock or the like and adapted to use with core or plug abrasive type bits commonly known as "diamond" bits. The drilling apparatus as a whole comprises bit rotating means generally designated 1, bit feeding means generally designated 2 and drill guiding and supporting means generally designated 3. The drill supporting and guiding means 3 is similar to that shown in said copending application and comprises a trunnion support 4 having a swivel plate 5 adapted to be secured in the saddle mounting of a conventional rock drill support.

The feeding means 2 likewise is similar to that shown in the copending application aforesaid and comprises a reciprocable feed cylinder 6 slidably guided in a bore 7 in the trunnion support and containing a reciprocable feed piston 8 having a tubular piston rod 9 extending forwardly through packings 10 carried by the front head 11 of the feed cylinder. The cylinder head 11 is suitably secured to the feed cylinder and closes the front end of the cylinder bore, while the rear end of the cylinder bore is closed by a rear cylinder head 12 likewise suitably secured to the cylinder. The front and rear cylinder heads are engageable with the end surfaces of the trunnion support 4 to limit reciprocable movement of the feed cylinder in the trunnion support bore. Secured to the front end of the feed piston rod 9 is a head member 13. The feed piston 8 is double acting and has packings 14 sealingly engaging the walls of the cylinder bore and secured in position by the members 15 and 16 in turn held in position on the rearward portion of the piston rod between a shoulder 17 and a detachable end plate 18, the latter secured as by screws 19 to the piston rod. Secured within the trunnion support 4 is a tube 20 having its axis arranged in parallelism with the feed cylinder axis, and extending longitudinally through this tube and rotatably mounted in depending bosses integral with the front and rear cylinder heads 11 and 12 is a tube 21, the latter having formed along a portion of the length thereof screw threads 22 coacting with the threads of a non-rotatable feed nut 23. The feed nut 23 is secured at 24 within the trunnion support 4. The forward end of the rotatable feed screw tube 21 is fixed against axial displacement with respect to the feed cylinder by a split ring 25 seated in external and internal grooves on the tube 21 and a detachable end plate 26 respectively, the latter secured to the front feed cylinder head 11. The feed screw tube 21 extends rearwardly through a bore 27 in the rear cylinder

head boss, as shown in Fig. 2, and has secured thereto a hand crank 28 having a grasping portion 29. Carried by the hand crank 28 is a spring-pressed plunger lock 30 having an operating handle 31 and engageable within a locking recess 32 in the rear cylinder head for locking the feed screw tube 21 against rotation during automatic feeding of the drill, as will later be explained.

As above mentioned, the forward end of the feed piston rod 9 supports the head member 13 (Fig. 1), and secured as by screws to the head member is a control head 35. Threadedly secured at 36 within this control head is a member 37 having a sleeve portion fitting within the bore of the feed screw tube 21 at the forward end of the latter, and secured as by welding at 38 to this sleeve portion is a tube 39 extending centrally within and in telescopic relation with the feed screw tube 21, in the manner shown in Figs. 1 and 2. The tube 39 has a sliding fit with the walls of the bore of the tube 21 and serves to maintain the feed cylinder against rotation within its bore on the trunnion support, and in effect acts as a lateral sliding guide for the drill.

The drill bit rotating means 1 comprises a rotary motor 40 herein a high speed electric motor of the totally enclosed type comprising a stator casing 41 provided with front and rear heads 42 and 43, the motor parts being held in assembled relation by tie bolts 44. The motor has a usual field 45 and an armature rotor 46, the shaft 47 of the rotor being journaled in bearings suitably supported in the motor heads. The rear motor head 43 has a rearward cylindric projection 48 mounted for limited rotation in ball bearings 49 supported within a bore formed in the control head 35. The bearings are retained in the control head bore by means of a retaining ring 50 secured as by screws 51 to the control head, and the cylindric projection is held against axial displacement with respect to its bearings by means of an end plate 52 secured as by screws to the projection 48. Electric energy may be conducted to the bit rotating motor 40 from any convenient source through a conventional connector plug 53 mounted on the control head 35 and connected through wiring 54 to the motor field 45, and a switch 55 is arranged in a chamber 56 in the control head for effecting starting and stopping of the motor in the manner fully described in the copending application above referred to. Suitably secured to the forward end of the motor rotor shaft is a chuck 57 which receives the supporting means for the drill rod which carries the drill bit. The purpose of the rotary mounting for the motor will be later explained.

Now referring to the means for supplying liquid under pressure to the hydraulic feeding means, it will be noted that formed in the control head 35 is a liquid supply chamber 60 to which liquid under pressure may be conducted through a strainer 61 from a supply passage 62 formed in a head member 63 secured as by bolts to the control head 35. A supply connection 64 (Fig. 16) is adapted to supply liquid under pressure to the passage 62 from any suitable source. Also formed in the control head is a longitudinal bore 65 having arranged therein a ported valve bushing 66 in which a control valve 67 is reciprocably mounted. This valve is of the sliding spool type and is held against rotation within the valve bushing bore by a pin 68 arranged in a transverse bore in the valve stem 69 and having its ends guided in longitudinal guide slots 70 in the member 37.

Also arranged in a transverse bore in the valve stem is a pin 71 having its ends projecting within an annular groove 72 in a rotatable member 73. This rotatable member has an integral valve adjusting screw 74 threadedly engaging a non-rotatable nut 75 formed within the sleeve portion of the member 37. The screw 74 is rigidly secured at 76 to a tube 77, this tube extending centrally within the tube 39 and being square in cross section and having telescopically arranged within its bore a square control rod 78 (Fig. 3). This rod extends rearwardly from within the feed screw tube 21 and is secured at 79 (Fig. 2) to a rotatable member 80 having a control handle 81. The rotatable member 80 is rotatably mounted within the bore of the tube 21 at the rear end of the latter and is held in position therein by a retaining pin 82 secured within the hub of the handle 81 and passing through an annular groove 83 in the member 80. It will thus be seen that by rotating the handle 81 the control valve 67 may be moved axially within the valve bushing bore through the rotatable screw 74 engaging the non-rotatable nut 75 integral with the member 37 and by the provision of the telescopically arranged square tube and rod the screw 74 may be rotated irrespective of the position of the control head relative to the trunnion support. Communicating with the rear end of the bore of the valve bushing is an exhaust chamber 85 connected by a passage 86 (Fig. 12) with an arcuate groove 87 in the head member 63 which in turn communicates with an exhaust passage 88 connected to atmosphere through an exhaust port 89 (Fig. 16). Surrounding the valve bushing are grooves 90 and 91 connected by ports with the valve bushing bore. A supply chamber 92 also communicates through ports with the valve bushing bore, while communicating with the front end of the valve bushing bore is an exhaust chamber 93, and a passage 94, controlled by a reverse-flow-preventing check valve 95, connects this exhaust chamber with the exhaust passage 88. The groove 91 is connected by a passage 96 in the control head with a passage 97 in the head plate 13, the latter passage communicating with the interior of the feed piston rod 9. Ports 98 (Fig. 2) connect the interior of the feed piston rod with the feed cylinder bore at the front side of the feed piston 8. Liquid under pressure may be supplied to the feed cylinder bore at the rear side of the feed piston from the supply chamber 92 through a passage 99, past a torque-controlled valve means generally designated 100, to a forward feed passage 101 communicating with a passage 102 in the head plate 13. The passage 102 connects the passage 101 with a recess 103 which is in turn connected by a liquid conducting tube 104 extending centrally rearwardly through the feed piston rod within the rear end of the feed cylinder bore at the rear side of the feed piston. The piston carries a packing 104' which sealingly engages the tube to prevent leakage. When the control valve 67 is in the position shown in Fig. 13, the feed cylinder bore at the front side of the feed piston may be connected to exhaust through ports 98, the interior of the feed piston rod, passages 97, 96, groove 91, ports in the valve bushing, exhaust chamber 85, passage 86, the exhaust groove 87 and exhaust passages 88 and 89. Also when the control valve 67 is in the position shown in Fig. 13, the feed cylinder bore at the rear side of the feed piston may be connected to exhaust through the tube 104, recess 103, passages 102, 101, past the automatic torque-controlled valve means 100 and through passage

99, chamber 92, the ports in the valve bushing, valve exhaust chamber 93, passage 94 and exhaust passages 88 and 89. When the valve 67 is in the position shown in Fig. 12 the reverse feed passages are connected to the supply groove and when the valve is shifted forwardly from the position shown in Fig. 13 the forward feed supply chamber 92 may be connected to the supply groove. This valve will hereinafter be described more fully. It will thus be seen that under the control of the control valve 67, liquid under pressure may be supplied to the feed cylinder bore at either side of the feed piston to effect forward or reverse feed as desired, and the manner in which the forward feed is influenced by the automatic torque-controlled valve means 100 will now be described.

The torque on the bit rotating motor 40 automatically regulates the flow of liquid under pressure through the forward feed passages under the control of the torque-controlled valve means 100 above referred to, in a manner similar to that described in the copending application Ser. No. 268,792 above referred to, and in the present invention the torque-controlled valve means has a further, venting, function whereby the forward feeding pressure may be vented when the torque on the bit rotating motor 40 exceeds a predetermined amount. The special utility of this feature will be shortly described. As previously described, the stator casing of the bit rotating motor 40 has limited rotation relative to the control head 35, and secured to the end plate 52 is a torque pin 105 (Figs. 1 and 7) engageable in a groove 106 in a reciprocable valve tappet 107. Tightly pressed in a transverse bore 108 in the control head 35 is a valve sleeve 109 having a conical valve seat 110 with which a sleeve valve 111 is engageable. A valve stem 112 integral with the tappet 107 has a tight sliding fit with the valve 111 and the valve is yieldingly held against a shoulder 113 on the valve stem by a coil spring 114. The valve 111 has an internal annular groove 115 connected by ports 116 with a chamber 117 which surrounds the valve. Formed in the valve stem is an axial passage 118 communicable through ports 119 with the internal groove 115 in the valve 111 in some positions of the latter relative to the stem, but normally sealed by the inner wall of the hollow valve. When the sleeve valve 111 is against the shoulder 113, as shown in Fig. 9, communication of the ports 119 with the groove 115 is cut off by the body of the sleeve valve, while when the parts are in the position shown in Fig. 10 the ports 119 are in communication with the groove 115. The valve sleeve is transversely slotted at 120, and this slot is connected by a port 121 with the chamber 117. The opposite side of the valve sleeve is transversely slotted at 122, and this slot is connected by a port 123 with an enlarged bore 124, the latter being communicable under the control of the valve 111 with the chamber 117. The passage 99 communicates with the slot 122 and the slot 120 communicates with the forward feed passage 101. As shown in Fig. 10, a longitudinal groove 125 on the exterior of the valve sleeve connects a chamber 126 at the outer end of the valve sleeve bore with a transverse slot 127 which is connected by passages 128 and 129 with the exhaust groove 87 which is in turn connected to exhaust through passages 88 and 89 as previously explained. The valve stem 112 has a sliding fit with the valve sleeve bore, and packings 130 sealingly engage the valve stem to 76

reduce the possibility of leakage. Any leakage of liquid along the valve stem may flow from the packing bore to the slot 127, as shown in Fig. 10. Threaded within one end of the valve sleeve bore 108 is a closure plug 131 while threaded within the opposite end of the valve sleeve bore is a plug 132, and interposed between the latter plug and the valve tappet 107 is a coil spring 133 which constantly urges the tappet toward the right as viewed in Figs. 4 and 7. The coil spring is arranged within a bore 134 in the plug 132, and the tappet is guided in this bore in the manner shown. When the tappet is in the position shown in Figs. 4 and 7 it may abut at its right hand end with the inner end of the valve sleeve 109, and when the tappet is in its extreme left hand position it may abut a shoulder 135 on the plug 132. The pressure exerted by the spring 114 on the stem 112 when the valve 111 is seated 20 is opposite to the direction in which the pin 105 tends to move the tappet 107 as a result of the torque reaction of the bit rotating motor 40, and the pressure exerted by the spring 133 is sufficient to hold the motor stator against rotation during normal full load drilling torque. The spring 114 is made of such strength that it will not yield and permit movement of the stem 112 relative to the valve 111, with resultant communication of passages 119 with groove 115, until a definite overloading of the motor occurs. The spring is preferably made about one quarter as strong as the main spring 133, plus an amount sufficient to offset the force due to the hydraulic pressure acting on the difference between the areas of the valve and valve stem. Noting that additional compression of the spring 133 will also have to be effected as overload increases, it will be apparent that a material overload, in excess by desirably upwards of 25% of normal full load, will be necessary on the motor before space 120 will be connected to vent. Now, it will be noted that if the load on the bit rotating motor exceeds a predetermined amount, i. e., if the resistance to motor rotation becomes excessive, the motor stator rotates slightly relative to the control head 35, thereby moving the torque pin 105 and valve tappet 107 to the left as viewed in Figs. 4 and 7, against the pressure of the spring 133; and as a result the valve 111 is moved toward its seat or completely seated, thereby partially to close or completely to cut off the flow of liquid under pressure from the passage 99 to the forward feed passage 101. If the load on the bit rotating motor becomes even greater 50 (which it may do despite the interruption of admission of feeding fluid, as will shortly be explained), i. e., if the resistance to motor rotation exceeds that which was previously predetermined as sufficient to warrant interruption of feeding, the motor stator will rotate slightly further relative to the control head, thereby moving the torque pin and valve tappet further towards the left, moving the valve stem relative to the seated valve 111 from the position shown in Fig. 9 into the position shown in Fig. 10, and as a result the forward feed passage 101 is vented through slot 120, port 121, chamber 117, the ports 116 and groove 115 in the valve 111, ports 119 and passage 118 in the valve stem, the chamber 126, groove 125, slot 127 and passages 128 and 129, groove 87 and exhaust passages 88 and 89. It is accordingly evident that variations in the load on the motor, due ordinarily to variations in the pressure with which the bit is forced to work, will automatically ef-

fect control of the flow of fluid relative to the space at the rear end of the feed cylinder and interrupt supply to this space as overload of sufficient degree occurs, and on still greater overload vent this space. It will be observed also that the leftward movement of the valve stem 112 beyond maximum venting position will, with the proportions shown, be precluded.

Again referring to the control valve 67, it will be noted that the same has spaced heads carrying packing rings and separated by grooves 140 and 141, the latter being of substantially greater width than the former. The valve has an axial chamber 142 and an end recess 143, and the groove 140 is connected with the chamber 142 through a series of ports 144 while the wide groove 141 is connected with the chamber 142 through a series of radial ports 145. Series of radial ports 146, 147 and 148 in the valve bushing connect the valve bushing bore respectively with the chamber 92 and grooves 90 and 91. When the valve is in the position shown in Fig. 12, the groove 141 connects the reverse feed groove 91 with the supply groove 90 so that liquid under pressure may flow from the supply chamber to the front end of the feed cylinder bore at the forward side of the feed piston. When the valve is in the position shown in Fig. 13, the feed cylinder bore at the forward side of the feed piston is connected to exhaust through the groove 91, ports 148, past the outer face of the rear valve head and through the valve bushing bore to the exhaust chamber 85. Concurrently, the feed cylinder bore at the rearward side of the feed piston is connected to exhaust through the chamber 92, ports 146 and ports 149 in the valve. When the valve is moved into its extreme position to the left from that shown in Fig. 13, the groove 140 connects the chamber 92 with the supply groove 90, so that pressure fluid may be supplied at that time to the forward feed passages while the reverse feed passages are connected to exhaust through groove 91 and exhaust chamber 85. The other positions of the control valve and its other functions are clearly described in the copending application above referred to. Arranged in one of a pair of aligned bores (Fig. 4) extending transversely and at opposite sides of the control head 35 is a manual control valve 152 which is adapted to control the flow of liquid under pressure to one side of a diaphragm 153 (Figs. 1, 6 and 18) which controls the actuation of the motor control switch 55 (Fig. 1). Arranged in the other bore is a manual control valve 154 which controls the supply of liquid under pressure through the motor rotor shaft and rod line to the drill bit. These control valves 152 and 154 are likewise fully described in the copending application above referred to.

The general mode of operation of the improved drilling apparatus is as follows. The apparatus may be set up in proper operating position with respect to the working face with the swivel plate 5 of the trunnion support suitably clamped in a saddle mounting of a suitable support, such as a mine column. The rod line is coupled by the chuck 57 to the motor rotor shaft and the drill bit is coupled to the rod line in a well known manner. Assuming that a starting hole has been made (this can be done in any suitable manner) and that the drill is aligned with this hole, the operator will then manipulate the control handle 81 of the control valve 67, moving the latter into a position to supply liquid under pressure to the

forward feed passages to effect forward movement of the feed piston 8 within the then stationary feed cylinder 6, thereby to feed the bit rotating motor forwardly to bring the drill bit within the starting hole at the working face against the bottom of the hole. Thereafter the control valve 67 is moved into a position to cut off flow of liquid under pressure to the forward feed passage, and, due to inherent leakage in the fluid line and the fact that a non-expansible fluid is used, the forward feeding pressure on the drill bit is reduced to a very low value substantially removing the feeding pressure from the drill bit. The operator may then adjust the control valve 154 to effect a supply of drilling liquid to the drill bit. Upon further manipulation of the control handle for the valve 67, the latter is moved into a position wherein liquid under pressure is supplied to the motor switch passages so that liquid pressure acts on the diaphragm 153 to actuate the motor switch 55 to start the bit rotating motor 40, and as a result the drill bit is rapidly rotated. Upon further manipulation of the control handle for the control valve 67, the latter is moved to a position to again supply liquid under pressure to the forward feed passages to effect forward movement of the feed piston within the then stationary feed cylinder to feed the bit rotating motor forwardly while the drill bit is rapidly rotated, thereby to effect drilling. The forward feeding pressure on the drill bit is sufficient to overload the bit rotating motor 40 in the event of any change in drilling conditions increasing above normal the torque requirements, and in the event of initiation of overloading of the motor, due to an excessive motor torque, the torque-controlled valve means 100 is actuated partially or completely to close the valve 111, thereby to reduce or completely cut off the flow of liquid through the forward feed passages to slow down or stop forward feed and preclude serious overloading of the motor, and when the motor again operates at its normal load rating, forward feed is automatically resumed or brought back to its desired rate, as the case may be. Thus the actual feeding pressure on the drill bit will always be kept at, or near, as an upper limit, that required to keep the bit rotating motor 40 working at its normal load rating, although the feeding pressure may be obviously greatly reduced or even entirely removed if conditions of drilling increase in difficulty. It will be apparent that sharp increases in torque requirements will entirely interrupt feeding fluid supply momentarily, and that slighter ones will serve to throttle the feeding fluid supply, and that depending on the pressure in the feed pressure supply line and the strength of the spring 133 the normal full load position of the valve 111 may vary.

A very important feature of the present invention may now be noted. The bit rotating motor 40 may be fed manually simply by manipulating the hand crank 28 to rotate the feed screw tube 21 relative to the non-rotatable feed nut 23, thereby to move the feed cylinder 6 forwardly in its guide bore on the trunnion support. And the feed cylinder can be moved forward relative to the feed piston while drilling is uninterrupted. As is the case with my earlier invention, when the feed piston has reached its limit of forward feeding travel relative to the feed cylinder, the control valve 67 may be positioned to supply liquid under pressure to the reverse feed passages to effect retraction of the feed piston, and the feed cylinder may then be fed forwardly in its

guide bore on the trunnion support into a new feeding position and thereafter forward feeding movement of the feed piston under the actuation of liquid under pressure may be resumed. Upon retraction of the feed, the motor switch 55 is automatically actuated upon initiation of liquid flow to the reverse feed passages to stop the bit rotating motor, thereby to stop rotation of the drill bit during reverse feed, this being desirable to prevent possible damage to the drill bit. Also during reverse feed the manual control valve 152 may be manipulated to interrupt the flow of drilling liquid to the drill bit. Also, if desired, the bit rotating motor may be fed either forwardly or rearwardly solely by the hand crank of the feed screw wholly independently of the flow of liquid under pressure to the feed cylinder. But we may now note the improved and novel mode of operation above mentioned. The improved torque-controlled valve means 100 comprises means whereby it is possible for the bit rotating motor 40 to be fed forwardly during the drilling operation without having to move the valve 171 out of forward feeding position. If, during forward feeding of the drill bit by liquid 20 acting on the rear pressure area of the feed piston, it is desired to feed the feed cylinder forwardly within its guide bore relative to the trunnion support by means of the hand crank of the feed screw, and so to move the cylinder forwardly 25 relative to the piston, the operator simply needs to turn the hand crank of the feed screw so as to advance the feed cylinder at a rate greater than the rate of penetration of the drill bit, i. e., at a rate greater than the drilling rate of the apparatus. This will obviously cause the normal feeding pressure on the drill bit to be increased and, as a result, the torque on the bit rotating motor 40 to become excessive, so that the torque-controlled valve means would move to the left 30 not only from the position shown in Figs. 4 and 7, if it happened to be there, but past the position of Fig. 9 perhaps to that of Fig. 10, i. e. sufficiently not only to effect seating of the valve 171 but also to move the valve stem to the left 35 relative to the seated valve, thereby to open the vent ports in the valve stem, and as a result the fluid in the rear end of the feed cylinder can be forced out as heretofore described through ports 116, groove 115, ports 119, bore 118, etc. The venting of liquid from the feed end of the rear cylinder at the rear side of the feed piston 40 enables manual advancing of the feed cylinder in its guide bore on the trunnion support by means of the hand crank for the feed screw. During this manual overloading of the bit rotating motor 40, the overload on the latter causes the torque to exceed the combined tensions of the springs 114 and 133 plus the liquid pressure on the differential area of the valve and valve 45 stem, thereby to cause the valve stem to move axially relative to the then seated valve 171, which permits the liquid trapped in the feed cylinder at the rear side of the feed piston to discharge through the feed exhaust passages. This venting function is at all times under torque control so that varied rates of venting, adapted to different rates of cylinder movement are obtained, and if the feed exhaust passages are of sufficient capacity the speed at which the operator manually feeds the feed cylinder forwardly has no substantial effect on the load on the bit rotating motor. Of course, after the feed cylinder has been advanced so that the rear cylinder head abuts the rear end of the feed piston, 50

and manual feed is continued by further movement of the hand crank, the bit rotating motor would be overloaded or stalled. The mechanism described enables the drill bit to be fed forwardly the combined distances of travel of the feed piston in the feed cylinder and the feed cylinder relative to the trunnion support without interrupting feed, thereby to enable reduction in the time consumed during drilling and eliminating the necessity of the operator's feeding the drill bit through a series of definite steps.

It is important to note that as the manual feeding means is operated to advance the feed cylinder relative to the working face at a rate below the rate of penetration of the bit, concurrent manual and automatic feeding is possible, the automatic feed, of course, being at a relatively slow rate as the valve 171 will be partially closed. If manual feed of the feed cylinder were to be effected at a rate exactly equal to the rate of penetration of the bit, liquid would neither enter nor be vented from the feed cylinder, during such feeding. If manually effected advance of the feed cylinder exceeds the rate of bit penetration, the valve 171 will be closed and fluid will be vented from the feed cylinder. This is, of course, the common mode of operation of the manual feeding means. At all times when automatic feed is held suspended because manual feed has superseded it, the automatic feed control is constantly ready to resume on discontinuation of manual feed.

As a result of this invention it will be noted that an improved drilling apparatus of the high speed rotary type is provided whereby holes may be bored in relatively hard material such as hard rock or the like, relatively quickly and efficiently. It will also be evident that an improved drill feed mechanism is provided having improved means for controlling the feeding pressure. It will still further be evident that an improved torque-controlled valve means is provided responsive to load changes on the bit rotating motor whereby the feeding pressure may be automatically controlled in accordance with varying degrees of resistance to drill bit rotation, and embodying means for automatically venting the feeding fluid when the load on the bit rotating motor is caused to exceed a predetermined amount. It will also be evident that by the provision of the automatic feed controlling means embodying a venting function, manual feeding of the drill at substantially any time during the drilling operation may be caused to supersede the automatic feed, thereby to facilitate and expedite feeding of the drill. It is worth noting, in part again, that under the control of the apparatus described there may be automatically effected, with feed rate automatically controlled by the torque-controlled valve, forward feeding due to regulated influx of feeding liquid into the feed cylinder, interruption of feed by cutting off of further influx of feeding liquid by the torque-controlled valve, combined manual and automatic feeding by operating the manual feeding means to effect cylinder movement at a rate less than the rate of penetration, manual feeding by advancing the feed cylinder and piston at a rate equal to the rate of penetration with neither addition nor discharge of liquid relative to the feed cylinder, and manual feeding and concurrent collapse of the forward feeding chamber provided by the cylinder and piston, by moving the cylinder forward more rapidly than the rate of penetration,

the connection between the source of feeding fluid supply and the feed cylinder then being closed and the vent opened by the assumption of the torque-controlled valve mechanism of a position similar to the one shown in Fig. 10. And the possibility of changing from automatic to manual feed at any time during the former, and of repositioning the feed cylinder at any time are important features. Other uses and advantages of the improved drilling apparatus will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a drilling apparatus, the combination comprising a drilling motor, fluid actuated feeding means therefor, means associated with said fluid actuated feeding means for manually feeding said motor, means automatically operative when a predetermined load on said motor is reached for automatically interrupting the flow of fluid to said feeding means and entrapping the feeding fluid therein, and associated means automatically responsive to an increased load on said motor due to increased loading of said motor by said manual feeding means for venting the previously entrapped feeding fluid while precluding the entry of further feeding fluid thereto.

2. In a drilling apparatus, the combination comprising a drilling motor, fluid actuated feeding means for said motor including a feed cylinder containing a reciprocable feed piston, means associated with said fluid actuated feeding means for manually feeding said motor and including means for feeding said feed cylinder into different feeding positions, means responsive to load changes on said motor for automatically controlling the flow of fluid under pressure to said fluid actuated feeding means, and associated means responsive to an increased load on said motor caused by manual feeding of said feed cylinder while the latter contains fluid by means of which a feeding pressure is exerted, for automatically venting such fluid at a rate to maintain forward feed while precluding excessive motor load increases.

3. In a drilling apparatus, the combination comprising a rotary drilling motor for rotating a drill bit, fluid actuated feeding means for feeding the drill bit toward the work comprising relatively reciprocable cylinder and piston feeding elements, manual means associated with said fluid actuated feeding means for feeding said feeding elements into different feeding positions, means responsive to the resistance to rotation of the drill bit for automatically controlling the flow of fluid under pressure to said feeding means, and means responsive to an excessive resistance to rotation of the drill bit due to overloading thereof by said manual feeding means through said fluid actuated feeding means for venting said feeding means thereby to permit manual feeding of the drill bit during the drilling operation by pressure transmitted through said fluid actuated feeding means while said fluid actuated

feeding means are maintained ready for automatic resumption of feeding.

4. In a drilling apparatus, the combination comprising a rotary drilling motor for rotating a drill bit, fluid actuated feeding means for feeding the drill bit toward the work comprising relatively reciprocable cylinder and piston feeding elements, manual means associated with said fluid actuated feeding means for feeding said feeding elements into different feeding positions, means responsive to the resistance to rotation of the drill bit for automatically controlling the flow of fluid under pressure to said feeding means, and means responsive to an excessive resistance to rotation of the drill bit due to overloading thereof by said manual feeding means for venting said feeding means thereby to permit manual feeding of the drill bit during the drilling operation while said fluid actuated feeding means are maintained ready for automatic resumption of feeding when manual feed is discontinued, the venting of fluid from said fluid actuated feeding means enabling the effecting of relative longitudinal movement between said cylinder and piston elements by said manual feeding means while a forward feeding pressure is maintained in said fluid actuated feeding means.

5. In a drilling apparatus, the combination comprising an electric motor for rotating a drill bit to cause the same to effect a drilling operation by a boring action, fluid actuated means for feeding the drill bit toward the work, and means responsive to load changes on said electric motor within certain predetermined limits for variably throttling the flow of fluid under pressure to said feeding means and embodying means automatically operative when said load limit is exceeded by a predetermined amount for venting the feeding pressure.

6. In a drilling apparatus, the combination comprising a rotary drilling motor of the high speed electric type having a stator and a rotor, fluid actuated feeding means for said motor comprising a feed cylinder containing a reciprocable feed piston, a support carried by the piston rod of said feed piston, means for mounting said motor on said support including means for journaling said stator for limited rotation with respect to said support, and a torque-controlled valve means carried by said support and operated by rotary movement of said stator with respect to said support, said valve means responsive to torque changes on said motor within certain predetermined limits for regulating the flow of fluid under pressure to said feeding means and embodying means for venting the feeding pressure fluid when said torque limit is exceeded.

7. In a drilling apparatus, the combination comprising a drilling motor of the high speed electric type having a stator and a rotor, fluid actuated feeding means for said motor comprising a feed cylinder containing a reciprocable feed piston and having reversible fluid supply connections, a guide on which said feed cylinder is guided for reciprocation, a support carried by the piston rod of said feed piston, means for mounting said motor on said support including means for journaling said motor stator for limited rotation with respect to said support, means associated with said fluid actuated feeding means for manually feeding said feed cylinder into different feeding positions relative to said guide, and controlling means including a torque-controlled valve means carried by said support and operated by rotary movement of said stator with respect

to said support, said torque-controlled valve means being responsive to torque changes on said motor within certain predetermined limits for regulating the flow of fluid under pressure to said feeding means and embodying means for venting the feeding fluid when said torque limit is exceeded by a predetermined amount, said venting function permitting manual feeding of said feed cylinder relative to said guide without reversal of the fluid supply connections for said fluid actuated feeding means, the venting of feeding pressure permitting movement of said feed cylinder by said manual feeding means relative to said feed piston.

8. In a drilling apparatus, the combination comprising a rotary drilling motor, feeding means for said motor, and means responsive to torque changes on said motor for automatically regulating the feeding pressure and embodying means for venting the feeding pressure when the motor torque becomes excessive, said torque-responsive means including a valve tappet guided for axial movement, a spring for opposing such tappet movement, said tappet having a valve stem provided with a shoulder, a sleeve valve surrounding said valve stem, a spring for yieldingly holding said sleeve valve against said shoulder, said sleeve valve adapted to seat when said first mentioned spring is compressed by a predetermined spring load to interrupt the flow of feeding pressure to said feeding means, and said valve stem adapted to slide relative to said seated sleeve valve when both of said springs are compressed when said predetermined spring load is exceeded to effect a venting function.

9. In a drilling apparatus, the combination comprising an electric motor for rotating a drill bit to cause the same to effect a drilling operation by a boring action, fluid actuated feeding means for the drill bit including a feed cylinder containing a reciprocable feed piston, the latter having a piston rod by which said motor is supported, and means responsive to torque changes on said motor due to variations in load on the drill bit for automatically interrupting flow of fluid to said feeding means and entrapping fluid therein and for thereafter venting the fluid therefrom.

10. In combination, a drill rotating motor, expandable chamber, fluid operated feeding means therefor, manual feeding means for feeding said expandable chamber feeding means to effect motor feed, motor torque controlled regulating means for said fluid operated feeding means, and motor torque controlled means operable upon creation of a predetermined pressure in said expandable chamber by operation of said manual feeding means for venting the expandable chamber feeding means.

11. In a feed controlling mechanism for a drill bit, a valve device comprising cooperating relatively movable valve parts movable concurrently to interrupt feeding fluid supply and thereafter movable one relative to the other to vent fluid previously supplied, and means controlled by variations in the resistance to drilling for automatically effecting such movements of said parts.

12. In a drilling apparatus, the combination comprising a rotary drill bit, a motor for rotating said drill bit, power operated means for feeding said drill bit, manually operated means for feeding said drill bit, said manually operated means being adapted to have its operation initiated while the power operated feed is taking place, and means whereby upon the development of an

increased resistance to bit rotation under the action of said manually operated means automatic interruption of operation of said power operated feeding means is effected, said power operated feeding means during such interruption being maintained ready for automatic resumption of feeding on the resistance to drilling decreasing to a predetermined extent by the discontinuation of manual feed, said means whereby automatic interruption of operation of said power operated feeding means is effected comprising feed control means which is adapted to effect such interruption of operation of said power operated feeding means by venting the feeding pressure.

13. In a drilling apparatus, the combination comprising a drill bit, a motor for actuating said drill bit to cause the same to effect a drilling operation, said motor including an element which provides the reaction necessary for the actuation of said drill bit, a motor support on which said reaction element is mounted for limited movement, means by which said reaction element is normally held against such relative movement while yet adapted when said motor is overloaded to move relative to said support, feeding means for applying a feed pressure to said drill bit and means for controlling the operation of said feeding means, said feed control means being adapted to operate automatically in accordance with variations in the resistance to drilling to preclude application of feeding pressures in excess of desired values to said drill bit, said feed control means also including means for automatically venting the feeding pressure when the resistance to drilling is above a certain amount, said motor reaction element being movable relative to said support to effect said feed control.

14. A drilling apparatus as claimed in claim 13, characterized in that the element of said motor which provides the reaction necessary for the actuation of said drill bit is mounted on said motor support for limited rotary movement relative thereto and is normally held against said relative rotary movement but is adapted when overloaded to rotate relative to said support and thereby to effect said feed control.

15. In a drilling apparatus, the combination comprising a drill bit, means for causing said drill bit to drill a hole including feeding means operative upon the supply of operating medium thereto to apply a feeding pressure to the drill bit, and controlling means automatically controlled by changes in the resistance to drilling for precluding the application by operation of said feeding means by operating medium supplied thereto of a feeding pressure in excess of a desired value to the drill bit, said controlling means including a reaction member which moves automatically from a normal position upon the resistance to drilling exceeding a predetermined value, said controlling means being actuated, in a direction to preclude such an undesired application of feeding pressure, by movement consequent upon a predetermined resistance to drilling of said reaction member, said controlling means including a torque-controlled valve means responsive to variations in resistance to drilling for automatically precluding feeding pressures in excess of desired values by diminishing or interrupting the supply of operating medium to said feeding means and for automatically venting the feeding pressure when the resistance to drilling is above a certain amount.

16. In a drilling apparatus, the combination

comprising a rotary drill bit, a motor for rotating said drill bit, a fluid actuated means for feeding said drill bit including relatively reciprocable feed cylinder and feed piston elements, manually operated means for feeding said drill bit, said manually operated means being adapted to have its operation initiated while the fluid actuated feed is taking place, means whereby upon the development of an increased resistance to bit rotation under the action of said manually operated means automatic interruption of operation of said fluid actuated means is effected, said fluid actuated means during such interruption being maintained ready for automatic resumption of feeding on the resistance to drilling decreasing to a predetermined extent as for instance by the discontinuation of manual feed, and feed controlling means whereby automatic interruption of said fluid actuated means is effected, said feed controlling means being adapted to effect such interruption of said fluid actuated feeding means by venting the fluid therefrom, said venting of fluid from said feeding means being adapted to enable relative longitudinal movement between said cylinder and piston elements by said manually operated feeding means.

17. In a drilling apparatus, the combination comprising a drill bit, means for causing said drill bit to drill a hole including feeding means operative upon the supply of operating medium thereto to apply a feeding pressure to the drill bit, and controlling means automatically controlled by changes in the resistance to drilling for precluding the application by operation of said feeding means by operating medium supplied thereto of a feeding pressure in excess of a desired value to the drill bit, said controlling means including a reaction member which moves automatically from a normal position upon the resistance to drilling exceeding a predetermined value, said controlling means being actuated, in a direction to preclude such an undesired application of feeding pressure, by movement consequent upon a predetermined resistance to drilling of said reaction member, said controlling means being operative to preclude such an undesired application of feeding pressure by interrupting the supply of operating medium to said feeding means and also embodying means for venting operating medium from said feeding means when said predetermined resistance to drilling is exceeded.

18. In a drilling apparatus, the combination comprising a drill bit, means for actuating said drill bit including a bit actuating motor, feeding means operative upon the supply of operating medium thereto to apply a feeding pressure to the drill bit, and controlling means automatically controlled by changes in the resistance to drilling for precluding the application by operation of said feeding means by operating medium supplied thereto of a feeding pressure in excess of a desired value to the drill bit, said controlling means including a reaction member operatively associated with said bit actuating motor and which moves automatically from a normal position upon the resistance to drilling exceeding a predetermined value, said controlling means being actuated, in a direction to preclude such an undesired application of feeding pressure, by movement consequent upon a predetermined resistance to drilling of said reaction member, said controlling means being operative to preclude such an undesired application of feeding pressure by interrupting the supply of operating medium to said

feeding means and also embodying means for venting operating medium from said feeding means when said predetermined resistance to drilling is exceeded.

5 19. A drilling apparatus as claimed in claim 17, characterized in that said reaction member is mounted on a support in said apparatus for limited movement with respect thereto, and is normally stationary with respect to said support and is moved relative thereto when the resistance to drilling attains a predetermined value, thereby effecting said actuation of said feed controlling means.

15 20. A drilling apparatus as claimed in claim 18, characterized in that said bit actuating motor comprises relatively movable parts of which one operates the bit and of which the other comprises said reaction member, a supporting member being provided for said reaction member with respect to which it is movably mounted and with respect to which it is adapted to move when resistance to drilling attains a predetermined value, thereby effecting said actuation of said feed controlling means.

25 21. In a drilling apparatus, the combination comprising an actuator for a drilling implement, power operated means for feeding the drilling implement, additional means for feeding the drilling implement, said latter means being adapted to have its operation initiated while the power operated feed is taking place, and means whereby upon the development of an increased resistance to drilling under the action of said additional feeding means automatic interruption of operation of said power operated feeding means is effected, said power operated feeding means during such interruption being maintained ready for automatic resumption of feeding on the resistance to drilling decreasing to a predetermined extent by the discontinuation of feed by said additional feeding means, and feed control means whereby automatic interruption of said power operated feeding means is effected, said feed control means being adapted to effect such interruption of said power operated feeding means by venting the feeding pressure.

30 22. In a drilling apparatus, the combination comprising a drill bit, a motor for actuating said drill bit, fluid operated means for feeding said drill bit, mechanical operating means for feeding said drill bit, said mechanical means being adapted to have its operation initiated while the fluid operated feed is taking place, and means whereby upon the development of an increased resistance to drilling under the action of said mechanical operating means automatic interruption of said fluid operated means is effected, said fluid operated means during such interruption being maintained ready for automatic resumption of feeding on the resistance to drilling decreasing to a predetermined extent by the discontinuation of feed by said mechanical means, and feed control means whereby automatic interruption of said fluid operated feeding means is effected, said feed control means being adapted to effect such interruption of said fluid operated feeding means by venting the fluid therefrom, said venting of the fluid enabling operation of said mechanical feeding means.

35 23. In a drilling apparatus, the combination comprising a drill bit, a motor for actuating said drill bit, feeding means for said drill bit operable on operating medium supply thereto for applying a feeding pressure to the drill bit, a device 40 for controlling the supply of operating medium

to said feeding means, means normally biasing said control device toward a supply effecting position, an element supported for movement under forces produced by resistance to drilling and adapted to move said control device under such forces in an opposite direction to effect interruption of the fluid supply and to effect venting of operating medium from said feeding means, said means normally biasing said control device toward its supply effecting position operative to hold said element stationary until until resistance to drilling attains a predetermined value.

24. In a drilling apparatus, the combination comprising a drill bit, a motor for actuating said drill bit to cause the same to effect a drilling operation, said motor including a rotary element operatively connected to the drill bit for rotating the latter, and a relatively stationary element, means for supporting said relatively stationary element for yielding movement under forces produced during drilling and varying with the resistance to drilling, feeding means for the drill bit for applying a feeding pressure to the drill bit, and means for controlling the operation of said feeding means, said feed-controlling means including an element operatively connected with said relatively stationary element and movable by the latter when resistance to drilling attains a predetermined value in a direction to effect venting of the feeding pressure to preclude application of feeding pressures in excess of desired values to said drill bit, said feed-controlling means being operative upon movement of said movable element to reduce the flow of operating medium to said feeding means and to vent the feeding pressure to preclude such an undesired application of feeding pressure.

25. In a drilling apparatus, the combination comprising an actuator for a drilling implement, power operated means for feeding the drilling implement, manually operated means for feeding the drilling implement, said manually operated means being adapted to have its operation initiated while the power operated feed is taking place, and means whereby upon the development of an increased resistance to drilling under the action of said manually operated means automatic interruption of operation of said power operated means is effected, said power operated means during such interruption being maintained ready for automatic resumption of feeding on the resistance to drilling decreasing to a predetermined extent as for instance by the discontinuation of manual feed, said means whereby automatic interruption of

5 operation of said power operated means is effected comprising feed control means which is adapted to effect such interruption of operation of said power operated feeding means by venting the feeding pressure.

26. In a drilling apparatus, the combination comprising an actuator for a drilling implement, said actuator including an element which provides the reaction necessary for the actuation 10 of the drilling implement, means for mounting said reaction element for limited relative movement, means for normally holding said reaction element against such relative movement but which when overloaded permits said reaction 15 element to move relative to its mounting means, feeding means for applying a feeding pressure to the drilling implement, and means for controlling the operation of said feeding means, said feed controlling means being adapted to operate automatically in accordance with variations in the resistance to drilling to preclude application of feeding pressures in excess of desired values to the drilling implement, said feed controlling means also including means for automatically 20 venting the feeding pressure when the resistance to drilling is above a certain amount, said reaction element of said actuator adapted upon such movement relative to its mounting means to effect feed control.

30 27. In a drilling apparatus, the combination comprising an actuator for a drilling implement, said actuator including an element which provides the reaction necessary for the actuation 35 of the drilling implement, means for mounting said reaction element for limited rotary movement, means for normally holding said reaction element against such rotary movement but adapted when the actuator is overloaded to permit rotation of said element relative to its mounting 40 means, feeding means for applying a feeding pressure to the drilling implement, and means for controlling the operation of said feeding means, said feed controlling means being adapted to operate automatically in accordance with 45 variations in the resistance to drilling to preclude application of feeding pressures in excess of desired values to the drilling implement, said feed controlling means also including means for automatically venting the feeding pressure when the resistance to drilling is above a certain amount, said reaction element of said actuator 50 adapted upon such rotary movement relative to its mounting means to effect such feed control.

CERTIFICATE OF CORRECTION.

Patent No. 2,288,543.

June 30, 1942.

WIN W. PAGET.

It is hereby certified that error appears in the printed specification of the above numbered patent requiring correction as follows: Page 6, first column, line 51, for the word "feed" read --rear--; line 52, for "rear" first occurrence, read --feed--; page 7, first column, line 53, claim 2, strike out the comma after "exerted"; page 10, first column, line 9, claim 23, after "device" insert --away--; line 11, strike out "until" first occurrence; line 21, claim 24, for "verying" read --varying--; and that the said Letters Patent should be read with this correction therein that the same may conform to the record of the case in the Patent Office.

Signed and sealed this 20th day of October, A. D. 1942.

Henry Van Arsdale,
Acting Commissioner of Patents.
